J. B. DOYLE

DOUGHNUT TRANSFER DEVICE

Filed April 30, 1925

Inventor

J. B. Doyle

By Watson E. Coleman

Attorney

UNITED STATES PATENT OFFICE.

JOHN B. DOYLE, OF BIDDEFORD, MAINE.

DOUGHNUT-TRANSFER DEVICE.

Application filed April 30, 1925. Serial No. 26,989.

To all whom it may concern:

Be it known that I, JOHN B. DOYLE, a citizen of the United States, residing at Biddeford, in the county of York and State 5 of Maine, have invented certain new and useful Improvements in Doughnut-Transfer Devices, of which the following is a specification, reference being had to the accompanying drawings.

10 This invention relates to a doughnut transfer device and it is an object of the invention to provide a device of this kind wherein doughnuts or the like may be readily transferred from the pans to a dipping 15 screen in a manner preventing injury to the doughnuts and more especially when of a jelly type.

The invention consists in the details of construction and in the combination and 20 arrangement of the several parts of my improved doughnut transfer device whereby certain important advantages are attained and the device rendered simpler, less expensive and otherwise more convenient and 25 advantageous for use, as will be hereinafter more fully set forth.

The novel features of my invention will hereinafter be definitely claimed.

In order that my invention may be the 30 better understood, I will now proceed to describe the same with reference to the accompanying drawings, wherein:

Figure 1 is a view in perspective of a transferring device constructed in accordance 35 with an embodiment of my invention with the several parts in separated relation together with the screen;

Figure 2 is a view in perspective of the supporting means for the hingedly mounted 40 members of the device, the coacting table or support being shown in fragment by dotted lines;

Figure 3 is a transverse sectional view of the device as herein disclosed in folded position before transferring the doughnuts;

Figure 4 is a view similar to Figure 3 showing the position of the parts for effecting a transfer.

As disclosed in the accompanying drawings, T denotes a table or kindred support 50 on the upper surface of which at predetermined points spaced therealong are the straps 1, said straps extending a slight distance in advance of the longitudinal edge 55 of the table and provided with bearings 2 for the elongated rod 3. The rod 3 out-

wardly of the bearings 2 but immediately adjacent thereto has freely engaged therewith the relatively short arms 4 terminating in the elongated arms 5 substantially at 60 right angles thereto. The arms 5 are secured to a board B of requisite dimensions and configuration. The arms 4 contact with the adjacent edge of the table T to maintain the board B in substantially a horizontal position in advance of the table T. The pan P is adapted to have placed therein the doughnuts or the like as molded by the baker and after said pan is properly filled, it is placed upon the board B when in the position illustrated in Figures 1 and 3 and it is to be noted that the board B is of greater 65 dimensions than the pan P mounted thereon. This permits the frame F to be positioned on the board B and surrounding the applied pan P, the side members 6 being of a height greater than that of the pan P.

A second board A has secured to a marginal portion thereof the straps 7 extending therebeyond and freely engaged with a rod 80 1 at points between the bearings 2.

After the frame F hereinbefore referred to has been applied, the dipping screen S is rested thereon with the lifting handles 8 for said screen downwardly disposed. The 85 board B is then swung down upon the applied screen S whereupon the boards A and B and the parts interposed therebetween are swung upwardly and rearwardly upon the table T as illustrated in Figure 4. This 90 results in the pan P being inverted with respect to the screen S so that when the board B is swung upwardly, the pan P may be readily removed leaving the doughnuts in proper position upon the screen S for dipping.

With my improved device, the production of doughnuts or the like is materially facilitated as the requisite application of the doughnuts to the screen is done by the 100 panful and thereby avoids the single transfer by hand of the doughnuts to the dipping screen as is now generally done.

It is to be understood that the screen S and the frame F as herein disclosed may 105 be of various different designs and may also be constructed for use in connection with different types of pans.

From the foregoing description it is thought to be obvious that a doughnut transfer device constructed in accordance with my invention is particularly well adapted 110

for use by reason of the convenience and facility with which it may be assembled and operated, and it will also be obvious that my invention is susceptible of some change 5 and modification without departing from the principles and spirit thereof and for this reason I do not wish to be understood as limiting myself to the precise arrangement and formation of the several parts 10 herein shown in carrying out my invention in practice except as hereinafter claimed.

I claim:—

1. A device for transferring doughnuts or the like to a dipping screen comprising, 15 in combination, with a support, a board pivotally engaged with the support, a second board pivotally engaged with the support and adapted to be swung in a position overlying the first named board, a frame adapted 20 to be applied between the boards and to sur-

round a pan mounted on one of the boards, and a dipping screen to be supported over the pan by the frame.

2. In a device for transferring doughnuts comprising, in combination, a support, arms 25 pivotally engaged with said support and terminating in angularly related arms, a board secured to said angularly related arms, a second board, means for pivotally connecting the second board to the support, said boards being adapted to be swung into overlying relation, the first named arms operating to maintain the first board in a pre-determined position, a frame adapted to be inserted between the boards and to surround a pan of doughnuts or the like and to provide a support for a dipping screen. 30

In testimony whereof I hereunto affix my signature.

JOHN B. DOYLE.
